United States Patent Office.

GEORGE RODNEY MOORE, OF PHILADELPHIA, PENNSYLVANIA.

Letters Patent No. 99,100, dated January 25, 1870.

IMPROVEMENT IN COAL-STOVES.

The Schedule referred to in these Letters Patent and making part of the same.

I, GEORGE RODNEY MOORE, of Philadelphia, in the county of Philadelphia, and State of Pennsylvania, have invented certain Improvements in Stoves and Heaters, of which the following is a specification.

The object of my invention is to provide a convenient mode of separating the refuse products of combustion from the burning fuel above them, so that ordinary coal-fires may be perpetuated at will.

Also, that the ash and cinder, which are the refuse products of combustion, may be conveniently removed at any time, without disturbing the fire above.

Also, to secure as favorable a draught as possible for the entire consumption of the coal, with all its escaping combustible gas.

I use no grate. The place ordinarily occupied by a grate, I leave nearly open and free to a hopper below, for the reception of the refuse products, as they are separated from and by the burning mass above, and from which hopper they are discharged, at will, by means of a slide cut-off just beneath it.

Figure 1 is a plan view of a common cylinder-stove, containing my improvements.

Figure 2 is a perpendicular middle section, and shows all the parts.

a is the ash-pit, which may receive a drawer.

b is a removable slide, shutting up the bottom of the hopper, and to be operated for the delivery of ash and cinder past it into the ash-pit.

c is the ash-hopper, and in this instance it is attached permanently, by narrow branches d d, to E, which is a ribbed circle, and is hung, so as to be vibrated easily, just below the fire-chamber, by means of the hand-lever f.

g is the lower portion of a fire-chamber.

The operation of the stove is as follows:

The draught is a side draught, h h h, in this instance extending entirely around, and just below the

fire-chamber, and occupying the space between the top of the hopper c, and the fire-chamber, or rather the ribbed circle e', which is at the base of the fire-chamber. The open part of the circle or ring e', is smaller than the top of the hoppers, so as to protect the draught from being quickly embanked by ashes.

Let the hopper be closed at the bottom by the slide b, and filled with either ashes or coal, a little above the draught; then kindle the fire, and feed it, as usual; and whenever the ash-hopper becomes so filled and heaped up, as to obstruct the draught too much, the slide beneath it should be operated to pass the required amount of its contents into the ash-pit or drawer below. And if, by reason of a self-bridging process, common with coal-fires, the whole mass needs urging downward, it is easily done by vibrating the ring e' by the lever f.

I claim, as my invention—

1. The ash-hopper e, or its equivalent, applied as a medium of communication from the fire-chamber to the ash-pit, substantially in the manner and for the purpose herein set forth.

2. The annular or side draught, accomplished without a grate between the ash-pit and the fire-chamber, and below the feed-door, substantially as and for the purpose herein set forth.

3. The ribbed ring e', or its equivalent, in combination with the fire-chamber above, and ash-hopper below, substantially as and for the purpose herein set forth.

4. The slide b, in combination with the hopper and ash-pit, substantially as set forth.

GEO. R. MOORE.
